APPARATUS FOR BALING PAPER PULP

Chester M. MacChesney, Chicago, Ill., assignor to
Acme Steel Company, Chicago, Ill., a corpora-
tion of Illinois

Application April 18, 1932, Serial No. 605,830

2 Claims. (Cl. 100—20)

This invention relates to apparatus for baling paper pulp and the like and its purpose is to provide an improved and more efficient apparatus by which a flexible binder may be inserted through a body of pulp and drawn taut around a portion of the pulp to form a bale. The present invention relates to the class of inventions described and claimed in the co-pending application of John Ekern Ott Serial No. 588,318, filed January 23, 1932.

The principal object of the invention is to provide an improved baling apparatus comprising means for compacting and moving an elongated mass of pulp in combination with a hollow needle which may be inserted through the pulp to permit flexible binders to be then threaded through the needle so that when the needle is withdrawn, the flexible binders are in position to be passed around units of the pulp in the succeeding operations of forming the completed bale. Other objects relate to various features of construction and arrangement which will appear more fully hereinafter.

The nature of the invention will be understood from the following specification taken with the accompanying drawings, in which one form of the improved apparatus is illustrated. In the drawings,

Fig. 1 shows a side elevation of one form of the improved apparatus adapted for use in practicing the method of the present invention;

Fig. 2 shows a horizontal section taken on the line 2—2 of Fig. 1;

Fig. 3 is a perspective view of the completed bale;

Fig. 4 shows an enlarged transverse section taken longitudinally through one of the needles, showing the method of threading the flexible binders through the hollow needle;

Fig. 5 is a transverse section on an enlarged scale taken on the line 5—5 of Fig. 1;

Fig. 6 is a longitudinal section taken through a modified form of needle; and

Fig. 7 is a longitudinal section taken through still another form of needle.

As illustrated in the drawings, the apparatus comprises a frame 10 having a pair of longitudinal frame members 11 in the form of I-beams which are adapted to rest upon the floor or other support. A casing 12 is secured to the upper flanges of these frame members 11 midway between their ends and this casing is adapted to receive the loose paper pulp through a hopper 13. The casing 12 has mounted therein a reciprocating piston 14 which is adapted to engage the pulp

in the casing and thereby compact it while at the same time forcing it from the casing into the elongated chute 15 through which the compacted pulp passes during the operation of forming it into bales. The piston 14 is operated by a piston rod 17 which is connected to a crank pin 18 eccentrically mounted between two large gears 19 which are secured on shafts 20 journaled in bearings 21 fixed on the frame members 11 and these gears are driven by pinions 22 fixed on a shaft 23. The shaft 23 is journaled in bearings 24 carried by the frame members 11 and a comparatively large gear 25 is secured to the outer end of this shaft to be driven by a pinion 26 secured on the shaft 27. The shaft 27 is journaled in bearings 28 carried by the frame members 11 and it has a flywheel pulley 29 secured thereon to be driven by a sprocket belt 30 passing around a pulley 31 fixed on the shaft of an electric motor 32. The mechanism for compacting the pulp may be started and stopped by starting and stopping the motor 32 and the speed of the compacting operation may be regulated by varying the motor speed. In addition, a friction clutch 33 may be connected in the train of mechanism between the motor and the gears 19 and this clutch is arranged to be operated through a shaft 34 which extends alongside the forward frame member 11 and has an operating lever 35 on the end thereof adjacent the hopper 13. The lever 35 may be locked in position by a detent engaging a quadrant 36 and in this way the operator is enabled to control the operation of the piston 14 from a position where he can view the pulp in the casing 12.

The chute 15 has a stationary bottom wall 40 formed by a pair of flat metal plates which are secured to the upper sides of the frame members 11, as shown particularly in Fig. 5. The side walls 41 of the chute 15 are formed of a series of flat plates 42 which are spaced apart to leave slots 43 extending parallel to each other longitudinally of the chute. The upper and lower plates 42 of each side wall are parts of angle bars 44 and the intermediate plates 42 are parts of T-bars 45. The bars 44 and 45 are connected at their forward ends to the rear end of the casing 12 by means of hinges 46 so that the rear ends of the side walls may be swung inwardly to cause the walls to converge toward their rear ends for the purpose of further compacting the pulp as it is moved along the chute. In order to effect the adjustment of the side wall members about the hinges 46, the bars 44 and 45 are connected together in pairs on each side of the wall, the horizontal flange of the lower beam 44

being connected through a bracket 47 with the web of the next adjacent T-beam 45 while the flange of the upper angle bar 44 is similarly connected by a bracket 47 to the web of the upper 5 T-bar 45. The brackets 47 are rotatably engaged by the inner ends of adjusting screws 48 which threadedly engage the side walls of yokes 49 and which are provided at their outer ends with squared portions 48^a adapted to be engaged by a wrench or the like. The yoke 49 has the lower ends of its side arms pivotally connected at 50 to brackets 51 which are secured to the frame members 11 and by adjusting the screws 48, the side plates 42 which form the side walls 10 may be adjusted inwardly or outwardly to vary the degree of compression to which the pulp is subjected as it is moved rearwardly along the chute.

The top wall of the chute 15 is formed by a 20 plate 52 which is carried by a number of T-beams 53 extending longitudinally of the chute and having their webs attached to angle bars 54. The angle bars 54 are engaged by adjusting members 55 which threadedly engage apertures in the upper 25 cross members of the yokes 49 and which may be turned for the purpose of varying the elevation of the top wall 52 or for causing it to incline downwardly toward the rear end of the chute. In this way, the spaced relation of the 30 top wall and the bottom wall 40 may be varied to regulate the cross-sectional dimensions of the bale and to vary the compression thereof under the influence of the piston 14.

The rear ends of the slots 43 which are formed 35 between the plates of the side walls of the chute are preferably occupied by friction plates or shoes 60 which are mounted at their rear ends on pivots 61 carried by brackets 62 fixed on the bars 44 and 45. These bars 60 have their forward 40 ends 60^a curved outwardly for the purpose of permitting the flexible binder to pass inwardly thereover as the pulp is moved rearwardly in the manner hereinafter described. In order to adjust the pressure with which these friction shoes 45 engage the flexible binders, they are adapted to be adjusted inwardly about their pivots 61 and this is effected by adjusting screws 63 which threadedly engage lugs 64 formed on the bars 44 and 45 which bear at their inner ends on the 50 outer sides of the friction shoes.

For the purpose of passing the flexible binders through the body of pulp as it moves rearwardly through the chute, the apparatus is provided with a plurality of hollow needles 70 which are 55 carried by a cylinder 71 extending transversely to the longitudinal axis of the chute. The inner ends of the needles 70 are secured to a hollow piston 72 which is adapted to move within the cylinder and which is formed of two parts united 60 by bolts 73. The piston has piston rings 74 engaging the inner wall of the cylinder, and it is adapted to travel from one end of the cylinder to the other in projecting the needles through the chute and withdrawing them therefrom. 65 The cylinder is closed at its outer end by a head 75 and at its inner end it is closed by a head 76 which is provided with apertures 77 through which the needles 70 are adapted to slide. Packing chambers 78 are formed in the head 76 70 around the needles and the packing material in these chambers is compressed by packing glands 79 which are forced inwardly by adjustable studs 80. The needles 70 are located in registry with the slots 43 in the side walls of the chute so that 75 when the piston 72 is forced to the inner end

of the cylinder 71, the needles are caused to pass through the slots 43 on both walls of the chute and thus penetrate the mass of pulp which is traveling rearwardly along the chute.

The movement of the piston 72 within the cylinder 71 is adapted to be effected by fluid pressure which is supplied through a flexible conduit leading to a pipe 81. This pipe leads into a four-way valve 82 which is controlled by a handle 82^a. Pipes 83 and 84 lead from the valve 82 to passages 85 which are formed in bosses 86 carried by the outer and inner ends of the cylinder, respectively, and these passages 85 communicate with the cylinder through ports 87. When the handle 82^a is in one position, the pipe 15 82 is connected with one of the pipes 83 or 84 and at the same time the other pipe, 84 or 83, is connected with an exhaust pipe 88 which leads from the valve casing 82 to the atmosphere. For the purpose of controlling the exhaust of compressed air or other fluid from one extreme end of the cylinder at the time that compressed air or the like is admitted to the other end of the cylinder, and thereby providing a cushion for the piston at the end of its stroke, the bosses 86 25 are provided with passages 89 which are inclined upwardly away from the passages 85 and which have U-shaped bends 89^a in the upper parts thereof to communicate with downwardly inclined portions 89^b which communicate with the 30 chamber of the cylinder through recesses 90 which are formed in the heads of the cylinder. The communication through each passage 89 is controlled by a needle valve 91 having a threaded engagement with the upper part of the boss 35 86 and being secured in adjusted position by a lock nut 92. When the piston 72 passes a port 87 toward either end of the cylinder, the exhaust of air or the like from that end of the cylinder through the port 87 is closed, with the result 40 that the remaining portion of air or the like in the end of the cylinder is trapped and can escape only through the adjacent restricted passage 89. This escape of air is gradual and may be regulated as desired by the needle valve 91 so that 45 the piston may be gradually brought to rest at each end of the stroke without undue shock to the cylinder or any of its parts. When the valve 82 is reversed, the compressed fluid is at first admitted to the last-mentioned end of the cylinder 50 through the passage 89 and this forces the piston in the reverse direction until it passes the adjacent port 87, whereupon there is a direct flow of compressed fluid into the cylinder for moving the piston toward the opposite end of 55 the cylinder, where the same cushioning action is again effected after the piston closes the other port 87 and entraps the air at the other end of the cylinder except for the gradual escape which is permitted through the other passage 89.

Since the needles 70 are adapted to be forced through the pulp while the pulp is in motion along the chute, the cylinder 71 is movably mounted so that it may move with the pulp. For this purpose, the cylinder 71 is provided on its 65 under side with flanges 95 which are connected by bolts 96 to a needle carriage 100 which is adapted to travel longitudinally of the machine on tracks 101 carried by brackets or frame members 102 which extend outwardly from one of 70 the side frame members 11, as shown in Fig. 5. The needle carriage is of rectangular form comprising longitudinal members 106 connected by transverse members 107 and at each corner of this carriage three cylindrical rollers are provided 75

to bear upon the track members 101. The members 106 of the carriage are of channel form as shown in Fig. 5 and these channels have mounted therein at each end a roller 108 which is adapted 5 to revolve about ball bearings 109 carried by a shaft 110 which is fixed in the walls of the carriage member. These rollers 108 are adapted to travel upon the upper horizontal surfaces of track members 101. In addition, the carriage 100 is provided with depending integral bracket portions 112 which are provided with channels or recesses in which are located other cylindrical rollers 113 adapted to bear upon the vertical flanges 101^a of the track members 101. These 15 rollers 113 are similarly mounted to revolve about ball bearings carried by shafts 114. On their inner sides, the track members 101 are provided with inclined portions 101^b which are engaged by other rollers 115 mounted within adjustable brackets 116. These rollers similarly revolve about ball bearings carried by shafts mounted in the brackets. The brackets 116 are secured to the under sides of the transverse members 107 of the carriage 100 by means of studs 117 enclosing 20 elongated slots therein. These slots permit the adjustment of the brackets so that the rollers 115 have a close engagement with the inclined portions of the track members 101 and they are held against movement, after being 25 adjusted, by means of the screw threaded adjusting members 118 which engage the ends of the brackets and which are arranged so that their heads bear on opposite sides of lugs 119 extending downwardly from the carriage. In this way, the carriage 100 on which the cylinder 71 is 30 mounted, is firmly supported so that the cylinder maintains a rigid position under the influence of the thrusts which are imparted thereto when the needles are forced through the pulp in the chute and at the same time the cylinder is permitted to move rearwardly with the travel of the pulp. After a predetermined rearward movement of the needle carriage, the needles are 35 withdrawn and the carriage is moved forwardly in readiness for the insertion of the needles at another point.

The needles 70 are pointed at their outer ends as shown at 70^a and they are provided with cylindrical bores 70^b extending throughout their 40 length, as shown in Fig. 4. Assuming that a body of pulp 120 has been compacted and is being moved intermittently rearward along the chute by the action of the piston 14, the operator admits compressed air to the outer end of the cylinder 71 to force the piston 72 inwardly and thereby cause the needle 70 to be thrust inwardly through the slots in the walls of the chute and through the body of the pulp 120 therein. The needles then occupy the position shown in Figs. 45 2 and 5 and while they are held stationary in this position, the operator then threads into each needle a flexible binder 121 and the end portion of another flexible binder 122, which may preferably be flat steel straps. If a flat steel strap- 50 ping is used for binding purposes, the bores of the needles 70^b may preferably be rectangular in cross-section with their longer dimensions extending vertically. After the first operation, the binder 121 will be one which has previously been 55 inserted through the mass of pulp and which has been partially drawn taut around one unit 120^a of the pulp while the binder 122 threaded into each needle will be one intended for passage around the next following unit 120^b of the pulp.

75 As shown in Fig. 2, a third unit 120^c of the pulp

has previously been bound by flexible binders 123. Assuming that the operation is at the stage illustrated in Fig. 2, the next step is to thread the free end 121^a of the binder 121 and one end portion 122^a of the binder 122 into each hollow 5 needle 70 and this threading operation is carried on until the ends of the binders reach the inner end of the bore of each needle, as illustrated in Fig. 4. The operator then admits compressed air to the inner end of the cylinder 71, whereupon the needles 70 are withdrawn from the pulp, thereby leaving the binders 121 and 122 in their proper positions passing transversely through the pulp adjacent to each other. With the apparatus illustrated, there will be three binders 15 121 and three binders 122 with two binders passing through the aperture made by one needle. When the needles have been withdrawn, the end 121^a of each binder 121 and the other end 121^b of each of these binders are brought together and 20 drawn taut, and then the overlapping ends of each binder are secured together by any suitable means, such as metallic seals 125, which may be of the form described and claimed in the patent to Ralph H. Norton No. 1,260,016, dated March 25 19, 1918. By the time the seals 125 have been applied, the unit 120^a will have been carried rearwardly along the chute and will then have the appearance of the bound unit 120^b illustrated 25 in Fig. 2. Before the next following unit 120^b of the pulp 30 continues its rearward travel, each binder 122 will have a considerable length at each side of the chute and these free ends of the strap are then engaged by the friction shoes 60 so that as the unit of pulp travels along the chute, these 35 shoes draw the binders taut around the pulp until they occupy substantially the positions illustrated in connection with the binders 121 in Fig. 2. The next operation is to cause the needles 70 to be again inserted through the pulp after 40 which the free ends of the binders on opposite sides of the chute from the cylinder are inserted into the needle as before along with the free ends of new binders preliminary to withdrawing the needles and thereby locating the straps in the 45 apertures which have been formed thereby through the pulp mass. In this way, each operation of the needle is utilized for effecting a second threading through the pulp of three binders which have previously been passed through the 50 pulp at a point spaced rearwardly therefrom and also for threading through the pulp three binders which are to be utilized in binding the next following unit of the pulp. By means of these 55 hollow needles, flexible binders may be readily threaded through the pulp without frictional resistance and the speed of operation is thereby greatly increased. It will be apparent that except for the lines of separation which are formed by the holes made by the needles, each unit of 60 the pulp mass remains attached to the next adjacent unit until it reaches the rear end of the chute and is projected outwardly to such a position that the line of division between two pulp units is beyond the walls of the chute. The 65 bound unit which is thus projected from the chute may then be broken off from the mass, by the action of gravity or by the application of force, to form the completed separated bale shown in Fig. 3.

In Fig. 6 of the drawings there is illustrated a modified form of needle 130 which may be substituted for the needles 10 illustrated in connection with the form of apparatus heretofore described. This needle is a straight hollow needle having an enlarged head 130^a which is tapered to a point as shown at 130^b and provided with a restricted opening 130^c therethrough to receive the strap or other flexible binder which is inserted into the needle, in the manner illustrated in Fig. 4, for the purpose of projecting the binder through the pulp while the needle is inserted therethrough. The needle having the enlarged head 130^a has the advantage that there is less friction developed by the operation of forcing it through the pulp and it may be more readily inserted and withdrawn than a needle which is of the same diameter throughout.

In Fig. 7 of the drawings, there is illustrated another modified form of needle 131 which is capable of substitution for the needles 10. This needle also has an enlarged head 131^a which is tapered on both sides of the large portion thereof and which terminates at its end in a sharp point 131^b. This form of needle has an enlarged passage 131^c, through which the strap is inserted into the needle, opening through the side of the tapered point of the head of the needle, as shown at 131^d. This permits the pulp to be more readily penetrated by the needle and effectively eliminates any difficulty arising from the clogging of the bore of the needle by small particles of pulp.

Although one form of the improved apparatus has been illustrated and described in connection with several forms of the needle, it will be understood that the apparatus may be constructed in various forms, falling within the scope of the appended claims.

I claim:

1. The combination in apparatus for baling paper pulp, of an elongated chute having longitudinal slots in its opposite walls, means for forming and moving through said chute a mass of paper pulp, a hollow needle movable transversely of said chute through said slots for penetrating the pulp therein, and means located in said slots for frictionally engaging a binder and holding it against the pulp during the travel thereof after it has been inserted through said pulp by threading it through said hollow needle.

2. The combination in apparatus for baling paper pulp, of a chute, means for forming and moving through said chute an elongated mass of pulp, a cylinder extending transversely to said chute, a piston mounted in said cylinder, a plurality of hollow needles secured to said piston and projecting from said cylinder, said chute having elongated slots in its opposite walls to permit said needles to pass therethrough, means for moving said piston in opposite directions in said cylinder, and supporting means for said cylinder to permit its movement parallel to the longitudinal axis of said chute.

CHESTER M. MACCHESNEY.

CERTIFICATE OF CORRECTION.

Patent No. 2,037,249.

April 14, 1936.

CHESTER M. MACCHESNEY.

It is hereby certified that error appears in the above numbered patent requiring correction as follows: In the grant, line 6, title of invention, for the word "BAILING" read BALING; page 4, second column, line 17, claim 1, strike out "it" and insert instead the words said binder; and that the said Letters Patent should be read with these corrections therein that the same may conform to the record of the case in the Patent Office.

Signed and sealed this 19th day of May, A. D. 1936.
